H. E. PRIVETT.

TOOL FOR REMOVING PERCHES FROM AUTOMOBILE AXLES.

FILED AUG. 27, 1921.

UNITED STATES PATENT OFFICE.

HORRY E. PRIVETT, OF LIVE OAK, FLORIDA.

TOOL FOR REMOVING PERCHES FROM AUTOMOBILE AXLES.

Application filed August 27, 1921. Serial No. 495,882.

To all whom it may concern:

Be it known that I, HORRY E. PRIVETT, a citizen of the United States, residing at Live Oak, in the county of Suwanee and State of Florida, have invented certain new and useful Improvements in Tools for Removing Perches from Automobile Axles, of which the following is a specification.

In attaching shock absorbers to different makes of automobiles, especially the Ford, it is necessary to remove the perch from which the body spring is suspended. Inasmuch as these perches, which pass through the axle, have a very snug fit through the axle and frequently become rusted in, it is a very difficult matter to remove them and when heavy hammer blows are required to dislodge the perch such blows destroy the threads on the perch or the lower edge of the perch becomes so distorted that it cannot be again used.

The object of my invention is to provide a perch remover which will enable one to readily, and without great effort, remove a perch without distorting the perch or its threads; and with this and other objects in view my invention consists of the parts and combination of parts as will be hereinafter pointed out.

30. In the drawings:

Figure 1 is a front elevation of the portion of an axle of an automobile, with my invention applied thereto.

Figure 2 is a side elevation of Figure 1.

35. Figure 3 is a top plan view of Figure 1, the perch being shown in section.

Figure 4 is a detail sectional view on the line 4—4 of Figure 2.

The reference numeral 1 designates an 40 axle of an automobile through which there are vertical openings near each end in which the perches 2 are sealed. The perches 2 are secured in the axle by means of the nut 3 which nut is mounted on the screw threaded 45 lower end of the perch and bears against the under face of the axle. The ends of the body springs of the automobile are secured to shackles which in turn are suspended from these perches.

50. My improved tool or device for removing these perches comprises a standard or body portion 4 having an enlarged head 5 from which arms 6 project at right angles to the body portion, said arms at their free ends 55 being offset from the general plane of the body of the arms as indicated at 7, the arms

being spaced so that they may straddle the body of the perch 2 as shown in the drawings.

A base member 8 extends at right angles 60 from the standard 4 in the same direction as and parallel to the body of the arms 6, its free end being provided with slots 9. A bolt 10 passes through the free end of the base 8 and straps 11 are pivotally mounted 65 on said bolt in the slots 9, the upper end of the straps 11 fitting into the forked ends 12 of the arms 6 and clamped in such position by means of the wing nuts 13. The base member 8 is widened at its free end portion 70 as shown. These widened portions of the standard and base enable me to secure a comparatively wide bearing for the tool or device on the axle to resist all tendency of the device to twist or work loose when in 75 use. The standard 4 is provided with a set screw 14 to hold the device snug to the axle.

A screw threaded thrust rod 15 is passed through an opening in the base 8 and a bevel gear wheel 16 is revolvably mounted on this 80 rod above the base 8, the gear wheel having threaded engagement with the rod.

A stub shaft 17 projects laterally from one side of the standards 4 on which a combined ratchet and bevel gear wheel 18 is 85 revolvably mounted, the bevel gear portion engaging the teeth of the bevel gear wheel 16. An operating handle 19 is loosely journaled on the stub shaft 17 and is provided with a nose 20 on which nose a ratchet dog 90 21 is loosely pivoted, said dog being offset at one end to bring it in alignment with the ratchet wheel 18. A cotter pin 22 holds the handle 19 on the stub shaft.

The nut 3 of the perch having been removed, my device is fitted around the axle as shown and clamped in position, the handle 19 is operated, whereupon the dog 21 revolves the ratchet wheel 18, the bevel gear thereof revolving the bevel gear 16, whereupon the rod 15 is elevated to a position with its end abutting the end of the perch 2; continued operation of the handle 19, through the operations just described causes the rod 15 to progress in its upward movement 100 against the lower end of the perch 2, thereby positively forcing the perch out of the axle in a minimum amount of time without great manual effort and avoiding distorting the lower end of the perch or its threads, so 110 that the perch may again be used.

I am aware that some changes may be

made in the details of construction without departing from the scope of the appended claims.

What I claim is:

- 5 1. A perch remover adapted to be removably secured to an axle of a motor vehicle having a main body portion, arms and a base extending from said body portion, straps pivotally connecting the free ends of 50 said arms and base, a gear wheel on said base, a thrust rod having threaded engagement with said gear wheel, a second gear wheel in geared relation with the first named gear wheel and an operating handle for the 55 second gear wheel.
- 10 2. A perch remover adapted to be removably secured to an axle of a motor vehicle having a main body portion, arms and a base extending from said portion, straps 60 pivotally secured to said base for connecting the free ends of the arms and base, a stub shaft extending from the body portion, a combined bevel gear and ratchet wheel journaled on said shaft, an operating handle 65 also journaled on said shaft, a ratchet dog on said handle adapted to engage said ratchet wheel, a bevel gear wheel on said base, and a thrust rod having threaded engagement with said bevel gear wheel.
- 15 3. A perch remover adapted to be removably secured to an axle of a motor vehicle having a main body portion, arms and a base extending from said portion, pivoted straps connecting the free ends of the arms and 70 base, a stub shaft extending from the body portion, a combined bevel gear and ratchet wheel journaled on said shaft, an operating handle 75 also journaled on said shaft, a ratchet dog on said handle adapted to engage said ratchet wheel, a bevel gear wheel on said base and a thrust rod having threaded engagement with said bevel gear wheel, and a set screw mounted in said body.
- 20 4. A perch remover comprising a main 80 body having a widened upper portion, spaced arms extending at right angles from 85 said upper portion, and provided with forked ends, a set screw in said body portion, a base extending at right angles from the body portion substantially parallel with said arms 90 and provided with slots in its free end, straps hingedly mounted in said slots at one end and adapted to engage the forked ends of the said arms at their other ends, a stub shaft projecting from said body, a combined bevel gear and ratchet wheel journaled on said shaft, an operating handle also journaled on said shaft, a dog pivotally secured to said handle and adapted to operatively engage the said ratchet wheel, a threaded thrust rod adapted to freely pass through an opening in the said base, a bevel gear wheel having threaded engagement with said rod above the base and also having operative engagement with the combined ratchet bevel gear wheel.
- 25 5. A perch remover adapted to be removably secured to an axle of a motor vehicle comprising a main body portion having arms and a base, means connecting said arms 95 and base, a thrust rod movable through said base, and gearing for operating said thrust rod.
- 30 6. A perch remover adapted to be removably secured to an axle of a motor vehicle, 75 comprising a main body portion having arms and a base, means connecting said arms and base, a thrust rod movable through said base, gearing for operating said thrust rod, and means for securing said perch remover 80 to an axle of a motor vehicle.
- 35 7. A perch remover for axles of motor vehicles comprising a main body portion, a bifurcated arm extending from said main body portion, a base extending from said main body portion, means connecting said arm and base, a thrust rod movable through said base, and gearing for operating said thrust rod.

In testimony whereof I affix my signature. 90

HORRY E. PRIVETT.
